UNITED STATES PATENT OFFICE.

CHARLES E. PENEZ, OF SAN FRANCISCO, CALIFORNIA.

DESIGN FOR A SOUVENIR-BADGE.

41,422.

Specification for Design. Patented June 6, 1911.

Application filed February 11, 1911. Serial No. 608,135. Term of patent 7 years.

To all whom it may concern:

Be it known that I, CHARLES E. PENEZ, a citizen of the United States, residing in the city and county of San Francisco and State of California, have invented a new, original, and ornamental Design for Souvenir-Badges, of which the following is a specification, reference being had to the accompanying drawing, forming a part thereof.

The figure is an elevation of my design for a souvenir badge.

I claim:

The ornamental design for a souvenir badge as shown.

CHARLES E. PENEZ.

Witnesses:

ARTHUR L. SLEE,
JAMES F. McCUE.
